UNITED STATES PATENT OFFICE.

ALONZO L. HASTINGS, OF CHICAGO, ILLINOIS.

PROCESS FOR CONSTRUCTING BOLSTERS.

1,077,709.

Specification of Letters Patent.

Patented Nov. 4, 1913.

Application filed January 20, 1912. Serial No. 672,272.

To all whom it may concern:

Be it known that I, ALONZO L. HASTINGS, residing at Chicago, in the county of Cook and State of Illinois, have invented certain new and useful Improvements in Processes for Constructing Bolsters, of which the following is a full, clear, and precise specification.

My invention relates to bolsters for railway trucks, particularly to an improved process for producing such bolsters.

Some of the bolsters of the prior art are formed more or less integral by ordinary casting processes, and in other cases the bolster has been built up of rolled iron or steel parts or has constituted a combination of iron or steel parts and cast parts. Castings are always more or less unreliable and consequently inefficient on account of blow holes and other flaws which are likely to occur. In built up structures considerable time is consumed in securing the various parts together, and the construction of the bolster is therefore more or less costly. Where the bolster is built up of a number of parts, rivets and bolts are sometimes used which are apt to work loose.

The important object of my invention is to provide an improved process for producing bolsters, such process involving the formation of the bolsters by drop forging suitable metal in a series of dies, the metal being preferably received in the first set of mold members direct from the melting crucible, and then treated in dies which are so constructed that the metal of the bolster can be compressed and worked transversely into uniform consistency of great strength.

The finished bolster of my construction is a single piece of metal having substantially the qualities of rolled steel and is entirely free from such defects as blow holes, which are always likely to occur where the ordinary casting process is used. The bolster formed in accordance with my process is also very much lighter and much stronger than the heavy bolsters formed by ordinary casting.

My improved bolster and the manner of its production are clearly illustrated on the accompanying drawings, in which—

Figure 1 is a side elevational view of the finished bolster, Fig. 2 is a top view thereof, Fig. 3 is an end view, Fig. 4 is a sectional view taken from plane 4—4, Fig. 1, Fig. 5 is a sectional view taken from plane 5—5,

Fig. 1, and Fig. 6 is a sectional view taken through upper and lower mold members and showing the embryo form therein looking from a plane corresponding to plane 4—4 in Fig. 1.

The finished structure comprises upper and lower longitudinal walls 10 and 11 whose section is substantially T-shaped similar to that of a T-beam, the central web stubs 12 serving to strengthen these walls. The opposite ends of the walls are connected together by webs 13, which webs form a continuation of the web stubs 12 on the walls. At each end are also transverse vertical walls 70 or webs 14 and 15, these walls, together with the webs 13, forming light yet strong box-like structures between the ends of the upper and lower walls 10 and 11. The sections 10^a of the upper wall deflect downwardly a 75 trifle, and the central portion 10^b is horizontal. The sections 11^a of the lower wall deflect upwardly, and the central section 11^b is horizontal. Connecting between the central sections 10^b and 11^b is a strut or standard 80 16 of circular cross-section and whose diameter increases gradually upwardly and downwardly from the central part thereof. On the middle section 10^b of the top wall and concentric with the strut 16 is the annular 85 flange 17 encircling the hub 18, the annular pocket 19 extending between the hub and the flange. The strut 16, together with the flange, hub and the pocket, serves to receive the king bolt mechanism on the body bolster 90 secured to the car with which the bolster will be associated, the hub and the strut being drilled axially at 20 to receive the king bolt. To prevent accumulation of dirt in the bottom of the king bolt bore the strut 95 has the transverse channel 21 communicating at its center with the lower end of the bore, so that any surplus grease, dirt or foreign particles may fall from the bore into the channel and thence to the exterior. In 100 order to further strengthen the strut, webs or ribs 22 are provided on the sides thereof continuous with the webs 12 of the upper and lower walls. On each upper wall section 10^a is a block 23 forming a foundation 105 for side bearing mechanism.

The end sections 10^c and 11^c of the upper and lower walls 10 and 11 are of slightly increased width, and the ends 11^c extend outwardly a distance beyond the upper sections 10^c, so that there will be ample bearing surface for springs which extend be-

tween the ends 11° and the spring plank when the bolster is applied to the side frames of the truck. The transverse walls 14 and 15 connecting between the sections 5 10° and 11° project beyond the sides of the sections to form abutment ridges 14' and 15' for receiving between them the faces of the column guides on the side frames of the truck, these ridges engaging the side edges 10 of the column guides and the edges of the sections 10° and 11° engaging against the faces of the column guides, this coöperation being well understood in the art. The particular shape and construction of the center bearing parts 17, 18 and 19 and of the side bearing blocks 23 will of course depend upon the particular style of center bearing mechanism and side bearing mechanism on the car body bolster with which the bolster 15 is to be associated. Likewise, the detail construction of the transverse walls 14 and 15 and the ridges 14' and 15' will depend upon the particular style of side frames of the truck with which the bolster is to be associated.

Coming now to the process for producing the single piece metal bolster above described, Fig. 6 illustrates substantially the initial step in the formation process. Mold 30 members *u* and *l* are suitably formed so that molten metal can be run therein direct from a crucible to form an embryo bolster frame which has substantially the same outlines as the finished bolster, but in which the walls 35 are transversely wider and longitudinally thinner than in the finished structure. After the poured metal becomes sufficiently cooled to be self-supporting, the embryo form is placed between die members and is 40 compressed transversely and increased in thickness to substantially the final form, this transverse compression and working causing the metal to become homogeneous and of uniform consistency and of great 45 tensile strength. After such die treatment the frame, although of substantially final shape, has burs and jagged ends thereon formed by the metal squeezing out between the die members during compression. This 50 frame, if not sufficiently hot, is re-heated and then treated in a second set of die members to be pressed and worked and trimmed and finished off to the final form.

After the die treatment the bolster structure does not have the bearing pocket 19 55 nor the bolster bore 20 nor the transverse channel 21. The pocket 19 and bore 20 may be formed in suitable machines, and the channel 21 may be punched into the strut 16 while the form is still hot after leaving 60 the dies.

I thus produce a complete bolster structure in the form of a single piece drop forging in which the metal, due to the compression and working in the various dies, has 65 substantially the same uniformity and consistency as the metal in rolled structures, there being no blow holes, flaws or other weaknesses. No metal is wasted, and the finished structure is very light yet possesses 70 very great strength. Substantially the same structure and process disclosed above can be applied to the car body bolster which is secured to the car body. On this car body bolster, instead of having the side bearing 75 blocks and the center bearing parts on the upper wall, these parts will be on the lower wall to coöperate with the side bearing blocks and center bearing parts on the truck bolster. The top wall of the car body bolster will of course be flat to intimately engage with the car floor.

I claim as follows:

The process of constructing bolsters for railway trucks, which consists in pouring 85 molten metal direct from the crucible between mold members to produce an embryo bolster structure whose walls are of greater width and less thickness than in the finished structure, then subjecting this embryo structure to die treatment and during such treatment working and compressing the walls transversely of the structure to bring the walls to substantially the same width and thickness as in the finished structure, then 90 subjecting such structure to a final die treatment to bring the walls to finished width and thickness and to trim off the edges of said walls.

In witness whereof, I hereunto subscribe 100 my name this 18th day of January, A. D., 1912.

ALONZO L. HASTINGS.
